DESIGN.

F. MANKEY.

MOLDING.

No. 16,958.

Patented Oct. 26, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,958, dated October 26, 1886.

Application filed July 1, 1886. Serial No. 206,875. Term of patent 7 years.

To all whom it may concern:

Be it known that I, FREDERICK MANKEY, of Williamsport, Lycoming county, Pennsylvania, have invented and produced a new and original Design for Trims or Moldings, of which the following is a specification, reference being had to the accompanying photograph, forming part hereof.

My design relates to an ornamental trim or molding in the form of a band or bar; and it consists in the configuration thereof, substantially as represented.

Upon the surface of the band are rhombic elevations A and B, with intermediate channels or depressions, C and D. Each elevation has two sides, E F, parallel and extending transversely across the band, and two sides, G H, standing inclined at an angle to said sides

E and F. The sides G H of the elevations A are oppositely inclined to the sides G H of the adjacent elevation B. The sides G H are shown as rounded or convex. On the edge of the band, at alternately opposite ends of the channels C and D, are recesses or indentations I and J.

I claim—

The design for an ornamental trim or molding, substantially as herein shown and described, which consists of the elevations A B, intermediate channels, C D, and edge recesses I J.

FREDERICK MANKEY.
